UNITED STATES PATENT OFFICE

JOHN ARTHUR CORBETT, OF HONOLULU, TERRITORY OF HAWAII, ASSIGNOR TO ROBERT LOVE ESTATE, LIMITED, OF HONOLULU, TERRITORY OF HAWAII, A CORPORATION OF HAWAII

DESIGN FOR A BOX COVER OR SIMILAR ARTICLE OF MANUFACTURE

Application filed December 12, 1929. Serial No. 33,768. Term of patent 14 years.

To all whom it may concern:

Be it known that I, JOHN ARTHUR CORBETT, a citizen of the United States, and a resident of Honolulu, in the city and county of Honolulu, Territory of Hawaii, have invented a new, original, and ornamental Design for Box Cover or Similar Article of Manufacture, of which the following is a specification, reference being had to the accompanying drawings, forming a part thereof, in which:

Fig. 1 is a plan view of the box cover.

Fig. 2 is a side elevational view thereof.

I claim:

The ornamental design for a box cover or similar article of manufacture, as shown.

JOHN ARTHUR CORBETT.
